UNITED STATES PATENT OFFICE

CALVIN B. P. CARVER, OF BRIDGEWATER, MASSACHUSETTS

CYLINDER FOR COTTON GINS OR THE LIKE

Application filed January 26, 1931. Serial No. 511,222.

This invention relates to an improvement in cylinders for cotton gins, linters, or the like.

The manufacturers and users of cylinders for cotton gins and linters often experience much difficulty both in manufacturing and repairing said cylinders because of the variations that occur in the thickness of the saw-blades. The cylindrical members upon which the saws are mounted are constructed to receive a definite number of saws spaced a definite distance apart by means of spacing members of certain definite thickness. It is evident, therefore, that if there is a variation in the thickness of the saws, especially when repairs and replacements are made, that the spacing of the saws will necessarily be changed and the total number of saws required to complete the cylinder may be increased or diminished.

The object, therefore, of this invention is to provide a cylinder of the type mentioned embodying therein a cylindrical member upon which are mounted alternately a plurality of thin disc-shaped saws and spacing members, the latter being so constructed and arranged with relation to each other and to the saws that slight variations in the thickness of the saws will not affect the spacing of the saws, the total number of saws required, or the effective length of the cylinder.

Another object of the invention is to provide an improved spacing member for the saws, said spacing members being provided with hub portions which are adapted to abut together end to end upon the cylindrical member, and said hub portions being grooved at one end thereof in a manner to permit the saws to be slidably mounted upon the cylindrical member between the spacing members.

The invention consists in a structure as set forth in the following specification and particularly as pointed out in the claims thereof.

Referring to the drawing:—

Fig. 1 represents a front elevation of a cylinder for a cotton gin or the like embodying my invention.

Fig. 2 is an enlarged transverse section

taken on the line 2—2 of Fig. 1, looking toward the left in said figure.

Fig. 3 is an enlarged transverse section taken on the line 2—2 of Fig. 1, looking toward the right in said figure, the saw blade 55 being omitted.

Fig. 4 is an enlarged detail sectional view as taken on the line 4—4 of Fig. 3.

Fig. 5 is an enlarged detail sectional view as taken on the line 5—5 of Fig. 3.

Like numerals refer to like parts throughout the several views of the drawing.

In the drawing, 6 represents a hollow cylinder having bearing portions 7 formed integral therewith at opposite ends thereof for the reception of a shaft 8 which may, if it is so desired, extend entirely through the cylinder 6, but which is preferably formed in two parts, said parts being rigidly fastened in the bearings 7.

Mounted upon the periphery of the cylinder 6 are a plurality of circular disc-shaped saws 9 and circular spacing members 10, said saws and spacing members being positioned alternately upon the cylinder for its entire length. At one end of the cylinder 6, the side surface of a saw 9 abuts directly against the side surface of a shoulder 11 that is provided upon said cylinder and all of the saws 9 and spacing members 10 are 80 placed upon the cylinder and removed therefrom from the opposite end.

Each saw 9 is provided with a central opening 12 which has a sliding fit with the periphery of the cylinder 6 and the edge of the opening 12 has a plurality of alternately arranged grooves 13 and projections 14 extending therearound, one of said projections having a tongue 15 formed thereon which is adapted to project into a groove 16 which extends longitudinally of the cylinder 6. The tongue 15 not only acts to prevent the saw 9 from rotating upon the periphery of the cylinder 6, but also acts to position the corresponding grooves 13 and projections 14 of all of the saws in alignment with each other.

Each spacing member 10 has a centrally disposed hub portion 17 formed integral therewith in which is a longitudinal open-

ing 18 permitting a sliding fit of the spacing member upon the periphery of the cylinder 6. A tongue 19 is formed upon the interior of the spacing member 10 and is adapted to fit the groove 16 that is provided in the periphery of the cylinder 6 and thereby prevent the spacing member from having a rotative movement upon the cylinder.

One face of the hub portion 17 of each spacing member 10 has a plurality of radial grooves 20 formed therein and when the spacing members are located in position upon the cylinder 6, the adjacent faces of said spacing members abut together end to end, and the grooves 20 of one spacing member co-operate with the face of the hub portion of the adjacent spacing member to form openings which extend through the hub portion from the periphery thereof to the periphery of the cylinder 6, and when a saw 9 is mounted upon the periphery of the cylinder between two spacing members 10 the projections 14 that are provided upon the saw will project through the grooves 20.

When the saws 9 are located in position upon the periphery of the cylinder 6 between two adjacent spacing members, the saw will project beyond the periphery of the spacing members through a space 21 that is provided between adjacent faces of the spacing members and this space 21 is sufficiently wide and the grooves 20 are sufficiently deep to permit the saw 9 to have a limited longitudinal sliding movement upon the periphery of the cylinder 6.

Mounted in the spacing members 10 and spaced at regular intervals therearound are compression members 22 constructed in the form of plungers 23 which are slidably mounted in openings 24 formed in the spacing member. Each plunger 23 has a flange 25 formed integral therewith which is located in a recess 26 provided in one face of the spacing member, and the plunger 23 is held within the opening 24 and recess 26 by means of a screw 27 which acts as a means of regulating the longitudinal movement of the plunger 23 within the spacing member and also as a means of varying the tension upon a spring 28 which is located within a recess 29 formed upon the interior of the plunger 23, one end of said spring abutting against the bottom of said recess and the other end of said spring abutting against the end of said screw.

The several saws 9 and spacing members 10 are all held in position upon the periphery of the cylinder 6 by means of a collar 30 and nut 31, the latter being adjustably mounted upon a screw-threaded portion 32 provided upon the shaft 8. When all of the saws 9 and spacing members 10 are located in position upon the cylinder 6, the various compression members 22 will engage a face of each of the saws 9 and yieldingly force the oppo-

site face thereof against the face of the adjacent spacing member and if there is any variation in the thickness of the saws the compression members 22 will compensate for this variation in thickness, whether it be an increase or a decrease from the correct thickness of the saw. It will be evident, therefore, that the cylinder 6 will always have a predetermined number of saws 9 and spacing members 10 mounted thereon; the spacing of the saws will not be appreciably affected and the effective length of the cylinder will always remain the same.

While I have illustrated and described this invention as being applied to the cylinder for a cotton gin or linter and the saws and spacing members as being adapted to be mounted upon a hollow cylindrical member, it is evident that other applications of the invention are possible and that wherever it is necessary to mount a plurality of disc-shaped members upon an arbor or equivalent structure, that spacing members embodying my invention may be utilized to space said members apart without departing from the spirit of this invention.

I claim:

1. A cylinder for a cotton gin or the like having, in combination, an arbor, a plurality of yieldable spacing members mounted upon said arbor, and a saw yieldingly mounted upon the arbor and positioned between each of the spacing members.

2. A cylinder for a cotton gin or the like having, in combination, an arbor, a plurality of yieldable spacing members mounted upon said arbor and abutting together end to end, and a saw yieldingly mounted upon the arbor and positioned between each of the spacing members.

3. A cylinder for a cotton gin or the like having, in combination, an arbor, a plurality of spacing members mounted upon said arbor, a saw mounted upon the arbor between each of the spacing members, and compression members interposed between each spacing member and saw and yieldingly engaging the latter.

4. A cylinder for a cotton gin or the like having, in combination, an arbor, a plurality of spacing members mounted upon said arbor, a saw slidably mounted upon the arbor between each of the spacing members, and compression members mounted upon the spacing members and yieldingly engaging the saws.

5. A cylinder for a cotton gin or the like having, in combination, an arbor, a plurality of yieldable spacing members mounted upon said arbor and embodying therein hub portions abutting together end to end, and a saw also mounted upon the arbor and positioned between each of the spacing members.

6. A cylinder for a cotton gin or the like

- having, in combination, an arbor, a plurality of spacing members mounted upon said arbor and abutting together end to end, a saw slidably mounted upon the arbor between each of the spacing members, and compression members yieldingly mounted upon the spacing members and holding the saws against adjacent spacing members. 5
7. A cylinder for a cotton gin or the like having, in combination, a cylindrical member, a plurality of spacing members mounted upon said cylindrical member, yielding means carried by said spacing members and a saw mounted upon the cylindrical member between each of the spacing members and engaging the yielding means. 10
8. A cylinder for a cotton gin or the like having, in combination, a cylindrical member, a plurality of yieldable spacing members mounted upon said cylindrical member and embodying therein hub portions abutting together end to end longitudinally, and a saw also mounted upon the cylindrical member and interposed between each of the spacing members. 20
9. A cylinder for a cotton gin or the like having, in combination, a cylindrical member, a plurality of spacing members mounted upon said cylindrical member and abutting together longitudinally, compression members mounted upon the spacing members, and a saw slidably mounted upon the cylindrical member between each of the spacing members and yieldingly engaging the compression members. 30
10. A cylinder for a cotton gin or the like having, in combination, a cylindrical member, a plurality of spacing members fast to said cylindrical member, a saw slidably mounted upon the cylindrical member between each of the spacing members, and a plurality of compression members interposed between the spacing members and saws and yieldingly holding each of the latter against a spacing member. 40
11. A cylinder for a cotton gin or the like having, in combination, a cylindrical member, a plurality of spacing members fast to said cylindrical member and embodying therein hub portions abutting together end to end, a saw mounted upon the cylindrical member between each of the spacing members and projecting beyond the periphery of the latter, and compression members interposed between the spacing members and saws and forcing each of the latter against a spacing member. 50
12. A cylinder for a cotton gin or the like having, in combination, a cylindrical member, a plurality of spacing members fast to said cylindrical member and embodying therein hub portions abutting together end to end, a saw mounted upon the cylindrical member between each of the spacing members, and a plurality of compression members slid- 60
- ably mounted upon each of the spacing members and yieldingly engaging each of the saws. 70
13. A cylinder for a cotton gin or the like having, in combination, a cylindrical member, a plurality of spacing members fast to said cylindrical member and embodying therein hub portions abutting together end to end, a saw mounted upon the cylindrical member between each of the spacing members, plungers slidably mounted upon each of the spacing members, and means to force each of said plungers against an adjacent saw. 75
14. A cylinder for a cotton gin or the like having, in combination, a cylindrical member, a plurality of spacing members fast to said cylindrical member and embodying therein hub portions abutting together end to end, a saw mounted upon the cylindrical member between each of the spacing members, plungers slidably mounted upon each of the spacing members, a spring adapted to force each of said plungers against an adjacent saw, and means to vary the tension upon said spring. 80
15. A cylinder for a cotton gin or the like having, in combination, a cylindrical member, a plurality of spacing members fast to said cylindrical member and embodying therein hub portions abutting together end to end and provided with grooves in a face thereof, a saw positioned between each of the spacing members and slidably engaging the cylindrical member through said grooves, and compression members interposed between the spacing members and saws and yieldingly holding each of the latter against a spacing member. 90
16. A cylinder for a cotton gin or the like having, in combination, a cylindrical member, a plurality of spacing members fast to said cylindrical member and embodying therein hub portions abutting together end to end and provided with grooves in a face thereof, a saw positioned between each of the spacing members and slidably engaging the cylindrical member through said grooves, a plunger slidably mounted upon each of the spacing members, and means to force each of said plungers against an adjacent saw. 100
17. A cylinder for a cotton gin or the like having, in combination, a cylindrical member provided with a groove extending longitudinally of the periphery thereof, spacing members mounted upon said cylindrical member having hub portions embodied therein abutting together end to end and provided with radial grooves in a face thereof, said spacing members also having a tongue embodied therein slidable in the groove of the cylindrical member, and a saw positioned upon the cylindrical member between each of the spacing members and having radial projections embodied therein engaging the cy- 110
- 120
- 125
- 130

cylindrical member through the radial grooves of the spacing members, said saws also having a tongue embodied therein slideable in the longitudinal groove of the cylindrical member and positioned to align the projections of the saws with the grooves of the spacing members.

In testimony whereof I have hereunto set my hand.

CALVIN B. P. CARVER.
